UNITED STATES PATENT OFFICE.

FRANCIS B. MCKINNEY, OF PITTSBURGH, PENNSYLVANIA, ASSIGNOR TO THE PARELLA CORPORATION, OF PITTSBURGH, PENNSYLVANIA, A CORPORATION OF PENNSYLVANIA.

UMBRELLA.

Application filed April 6, 1928. Serial No. 287,961.

The invention relates to temporary or emergency umbrellas, of the type which are adapted to be sold for a small sum, or which are to be given away by merchants and other 5 business people for advertising or other purposes.

The objects of the invention are to provide an umbrella of the class referred to which is of the simplest possible construction and 10 which entirely dispenses with the ribs, auxiliary handle and other additional parts of the ordinary umbrella structure; which can be manufactured easily and at low cost from a minimum of inexpensive material; is easily 15 shipped and requires a minimum of storage space, is sufficiently rigid for its intended purpose, is easily put in condition for use, and which is highly efficient as an emergency substitute for the usual umbrella.

20 In its simplest and preferred form the umbrella according to the invention consists of a unitary structure made from a sheet of a self form-sustaining, sufficiently water-proof material, which is provided with adjacently disposed, substantially straight lines of weakness extending inwardly from the edge of the sheet and intersecting at a material distance from the edge. When the umbrella is to be used, the material between the 25 lines of weakness is folded in, causing the sheet to assume a conical form, and the in-turned folded material provides a gripping member which, when held together, maintains the sheet in its conical or umbrella-like 30 form.

The preferred embodiment of the invention is illustrated in the accompanying drawings, in which Fig. 1 is a plan view of a sheet of material as prepared and before bending; 35 Fig. 2 is a front elevational view of the sheet shown in Fig. 1 partly formed into the umbrella; Figs. 3 and 4 are front and side views respectively showing the completed umbrella ready for use; and Fig. 5 is a plan view of a 40 modified sheet, before bending.

45 Referring to Fig. 1, a sheet 1, of a flexible material possessing the necessary rigidity to make it self form-sustaining when shaped, without necessitating the use of any reinforcement, and sufficiently water-proof, such as a calendered or paraffined cardboard, is scored or otherwise provided with substantially straight lines of weakness 2 and 3. As shown in the drawing, these lines of weakness are

adjacent to each other, and they extend from the edge of the sheet to a point materially within the sheet, in this case to the center of the circular sheet shown. Preferably the sheets are transported and stored in this condition, as they are then easier to pack and handle. When the umbrella is to be used, the material included in the segment bounded by the lines 2 and 3 is bent inwardly, the first 55 stage being shown in Fig. 2. As the bending continues, the lines 2 and 3 approach each other, and the sheet assumes a conical form. This operation results in the conical, umbrella-like shape shown in Figs. 3 and 4, and the completely folded material provides a gripping member 4. This member is grasped 60 in the hand, and provides a handle for supporting the umbrella, and, by holding the fold tightly, the umbrella is maintained in its conical form.

65 It will usually be desirable to provide a third line of weakness 5 in order to assist in the folding operation. In this case, the line of weakness 5 will be formed on one surface and lines 2 and 3 on the opposite surface, and it will generally be desirable to so dispose line 5 that lines 2 and 3 are equi-distant 70 from it.

75 Although circular sheets are preferably used, the invention is equally applicable to other configurations such as a square sheet 80 6, Fig. 5, which is provided with lines of weakness, as in the preceding embodiment. Although I prefer to form the lines of weakness 85 to intersect at the center of the sheet, this disposition is not absolutely critical, and 90 satisfactory results can be secured if these lines extend to a point situated materially within the sheet, as shown in Fig. 5.

95 Another modification applicable to any form of sheet is shown in Fig. 5, and this consists in punching slots 7 and 8 in the portion to be folded, the slots being disposed to register when the fold is made. They thus provide an opening through which some or all of the fingers may be passed, for greater ease 100 of holding the umbrella.

105 The umbrella according to the invention can be made very inexpensively inasmuch as the only material required is a sheet of suitable material, it can be made in a single operation, and no supplementary strengthening or handle members are necessary, thus eliminating the cost of producing those parts and as-

sembling them. The umbrella thus provided is easy to operate and is efficient in action, and from substantially all standpoints it is more satisfactory for its purpose than other forms of emergency umbrellas heretofore produced.

The umbrella provided by the invention is especially suitable for distribution to persons congregated outdoors, as at fairs, races, 10 athletic events, or other gatherings, to supply adequate protection against sudden or unexpected inclement weather. Where desired, they may be sold for a small sum. However, by printing advertising matter on the 15 umbrellas, they provide an excellent and very inexpensive publicity medium for free distribution.

According to the provisions of the patent statutes, I have explained the principle and 20 mode of operation of my invention, and have illustrated and described what I now consider to be its best embodiments. However, I desire to have it understood that, within the scope of the appended claims, the invention 25 may be practiced otherwise than as specifically described.

I claim:

1. An emergency umbrella consisting of a sheet of self form-sustaining material provided with adjacently-disposed straight lines 30 of weakness extending from the edge to a point materially within the sheet, the portion

of the sheet between said lines of weakness being turned inwardly to form a gripping member which when engaged maintains the 35 sheet in conical form.

2. An emergency umbrella consisting of a sheet of self form-sustaining material provided with three adjacently disposed and 40 equally spaced lines of weakness extending from the edge to a point materially within the sheet, the portion of the sheet between the outer two lines of weakness being turned inwardly and folded along the central line of weakness to form a gripping member which when engaged maintains the sheet in conical form.

3. An emergency umbrella consisting of a circular sheet of self form-sustaining material provided on one surface with two adjacently-disposed lines of weakness, and on the other surface with a third line of weakness spaced equi-distant between the first-named lines of weakness, all of said lines of 50 weakness extending from the edge to a point materially within the sheet, the portion of the sheet between the outer two lines of weakness being turned inwardly and folded along the central line of weakness to form a gripping member which when engaged maintains the 55 sheet in conical form.

In testimony whereof, I sign my name.

FRANCIS B. McKINNEY.
